J. H. DEAN

FURRING CLIP

Filed Dec. 24, 1927

Inventor
James H. Dean
by Arthur W. Nelson, Atty.

UNITED STATES PATENT OFFICE.

JAMES H. DEAN, OF LUDINGTON, MICHIGAN.

FURRING CLIP.

Application filed December 24, 1927. Serial No. 242,337.

This invention relates to improvements in furring clips and it consists of the matters hereinafter described and more particularly pointed out in the appended claims.

5 The primary object of the invention is to provide a simple and efficient metallic clip adapted for use in connection with a nail for securing metallic lath or similar fabrics, together with an associated paper sheathing to 10 a building wall or the like.

Another object of the invention is to provide a clip of this kind which may be readily made and which together with its nail, may be driven with a single hammer blow into 15 the wall to hold the paper and be left in a condition to receive desired portions of the lath or fabric to be applied to the wall after which another hammer blow drives the nail home and clamps the lath or fabric portion 20 in place, the proper spaced distance from the wall.

Still a further object of the invention is to provide a clip of this kind which includes a body and a paper engaging base with a tongue 25 parallel therewith but spaced therefrom the distance desired to space the lath or fabric from the wall, which tongue is formed from a part of the body and is so arranged with respect thereto as to amply resist bending 30 stresses under hammer blows on the nail passing therethrough, said base and tongue so frictionally gripping the nail that the same cannot be displaced therefrom.

These objects of the invention as well as others together with the many advantages 35 thereof will more fully appear as I proceed with my specification.

In the drawings:

Fig. 1 is a vertical sectional view on an enlarged scale through a clip embodying one 40 form of the invention, together with its associated nail, in position upon a building wall for securing the sheathing paper and metallic lath or similar fabric thereto.

Fig. 2 is a view in front elevation thereof, 45 with the nail head omitted to more clearly disclose the construction of the clip.

Fig. 3 is a perspective view of the clip.

Fig. 4 a view in elevation of a blank from 50 which the clip shown in Fig. 3 is formed or made.

Fig. 5 is a view similar to Fig. 1 illustrating a modified form of clip embodying the invention.

Fig. 6 is a view in front elevation of the 55 clip shown in Fig. 5.

Fig. 7 is a perspective view of the clip shown in Figs. 5 and 6.

Fig. 8 is a view in elevation of a blank from which the clip of Fig. 7 is made. 60

Referring now in detail to that embodiment of the invention illustrated in Figs. 1 to 4 inclusive of the accompanying drawing, 1 indicates as a whole, the clip with which is associated an ordinary nail 2; the clip being 65 an integral structure made from a single piece or blank of sheet metal as best shown in Fig. 4. The clip comprises a rectangular body 3 and a base 4 at one end thereof, arranged at a right angle thereto by being bent 70 from one side of the body along the line 5. Punched out from the midportion of the body and bent along the line 6 so as to be parallel with and overhang the base but spaced therefrom is a tongue 7, which ordinarily forms the spacing element of the clip. 75 At the lateral margins of the body are flanges 8—8 bent along lines 9—9 to extend at a right angle to the body. Each flange overhangs the base and one of its end edges 10 bears upon said base while its other end edge terminates preferably in the plane of the tongue 7 to there provide shoulders 11—11. Disposed centrally in the tongue is an opening 12 which registers with a similar opening 13 in the 80 base, said openings being a trifle smaller in diameter than the shank of the nail 2 and being defined by annular burs 12^a and 13^a respectively.

When the clip and nail are in their assembled relation, the clip is positioned upon the shank 2^a of the nail (which passes through the burred openings 12^a and 13^a respectively) about midway between the point 2^b and head 2^c thereof, this relative position being best 90 indicated in dotted lines in Fig. 1.

Assume that it is desired to secure a metallic expanded lath or like fabric 14 in spaced relation to a building wall 15 which includes the studding 16 and siding 17, with a paper sheathing 18 upon said siding. In applying the paper sheathing to the siding, a nail with a clip 1 thereon is driven through the paper sheathing and siding and into the studding until the base 4 of the clip engages the paper sheathing. The base being engaged with the paper, presents its entire area thereto with enough pressure to securely hold the sheathing in place so that it will not fall or tear under its own weight. 100

In applying the clip and nail mentioned it is preferable that the body be disposed below 110

the nail. In hanging the fabric 14 previous to securing it in place the strand portions thereof convenient to the clips are engaged upon the free marginal parts of the body 3 5 beyond the tongue 7 and then moved into engagement with said tongues 5 under the nail shank 2^a and when in this position said strands will also engage against the end shoulders 11—11. The nail head is then 10 struck a hammer blow to drive it home and when thus driven home will engage upon the free edge of the body portion and thus secure the strands in place, in spaced relation to the paper sheathing, which spaced relation 15 is determined by the distance between the base and tongue. In this driving home of the nail, should the nail be struck after its head engages the edge of the body as mentioned, the flanges 8—8 so stiffen and brace 20 the body that it cannot bend over under the force of the blow. Thus the strands are securely held in position and are engaged at opposite sides by the body and nail shank and at opposite edges by the tongue and nail head. 25 In this connection it is pointed out that as the strand engages that part of the tongue closely adjacent the body said tongue acts as a rigid shoulder therefor. By reason of the burs 12^a and 13^a on the tongue and base respectively, 30 the nail is so securely held by frictional engagement that it indeed is difficult to separate the nail and clip.

In Figs. 5 to 8 inclusive I have illustrated a slightly modified form of construction 35 wherein substantially the same advantageous features are present. As best shown in Fig. 7 the modified form of clip 20 is made up from the blank shown in Fig. 8 and is folded along the lines 21—22 to provide a body 23, a base 24 arranged at a right angle thereto and a flange 25 parallel with the body, the 40 flange being of a height less than that of the body and which height approximates the width of the base. Punched out from the body is a tongue 26 which is bent over along the line 27 to extend parallel with the base but still attached at one end to the body and resting at its free end upon the edge of the flange 25. In providing this tongue from a 45 punched part of the body, it is apparent that a recess or notch 28 will be provided in the free edge of the body between the shoulders 29—29 at each side edge thereof, and in the base and tongue, respectively, are provided 50 registering and annularly burred openings 24^a and 26^a for the passage of a nail shank 2^a.

When such a clip and associated nail are employed to secure the fabric 14 in place, the clip is disposed upon the nail about midway 55 between the ends thereof. The nail is then driven through the paper sheathing 18 and

siding 17 and into the studding 16 until the base 24 engages the paper sheathing and holds it in place, the head being positioned a distance beyond the shoulders 29—29 as the 65 body. The fabric 14 is then hung upon the shoulders 29—29 and the nail is then driven home, a portion of the head 2^c thereof being engaged in the recess 28, with the strand portion of the fabric securely clinched between 70 the nail shank and head and tongue 26 and shoulders 29 all as best shown in Fig. 5. It is herein pointed out that with the tongue resting at its free margin upon the flange 25 as described a strong rigid structure is provided which cannot be distorted should the nail head be struck after engaging in the recess. 75

Both forms of the improved clip above described are readily made from strip stock by 80 automatic machinery. They are light in weight and though simple in construction are indeed efficient for their intended purpose.

While in describing my invention, I have referred in detail to the form and arrangement of the various parts thereof, the same is to be considered as illustrative only so that I do not wish to be limited thereto except as may be pointed out in the appended claims. 85

I claim as my invention:—

1. In combination with a clip comprising a body having one end bent over from one side thereof to form a flat right angle base and having side portions bent over to engage upon said base but terminating short of the other end of the body to provide shoulders, the midportion of the body being punched out and bent along a line in the plane of said side shoulders to provide a tongue parallel with but spaced from the base, said base and tongue having aligned openings therein to receive the shank of a nail having a head, which when the nail is driven home into a building wall coacts with the tongue, body and shoulders to securely hold a fabric part in spaced relation with respect to the building wall. 95

2. A furring clip comprising a body portion having one end bent over to form a right angle base and having its side margins bent to form flanges which overhang and have an edge like engagement at one end on said base and terminate at their other end short of the other end of the body to provide end shoulders thereon, the midportion of the body between said side flanges being formed to provide a tongue parallel with the base, said tongue and base having registering openings therein to receive the shank of a nail. 105

In testimony whereof, I have hereunto set 110 my hand, this 20th day of December, 1927.

JAMES H. DEAN.
